CLAIM

The ornamental design for an electric cleaning brush, as shown and described.

DESCRIPTION

FIG. 1 is a front, left and top perspective view of an electric cleaning brush, showing my new design;
FIG. 2 is a rear, right and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof; and,
FIG. 9 is a perspective view of the electric cleaning brush where the electric cleaning brush is in a configuration of use. The broken lines shown in the drawing illustrate portions of the electric cleaning brush that form no part of the claimed design.
